COIN CONTROLLED TIMED SERVICE DEVICE

Thomas A. Isele, Richmond Hill, N. Y., assignor to Superior Meter Company, Brooklyn, N. Y., a corporation of New Jersey

Application December 5, 1932, Serial No. 645,792

27 Claims. (Cl. 194—55)

Coin controlled devices are extensively employed for rendering conveniently available to the public a wide variety of service. The construction and manner of operation of the coin controlled mechanism of such a device is to a considerable extent determined by the nature of the service to be rendered available. The coin controlled device of my present invention, as herein disclosed in several forms thereof, is in the nature of a timed service-supplying device, for inaugurating the service to be supplied thereby and then, after a predetermined period of time has elapsed, for discontinuing such service, so that thereby the service rendered available is provided only over a predetermined limited period of time, for each coin controlled operation of the device. While the coin controlled service-supplying device of my present invention is shown herein as in timed control of a supply of combustible gas, it is to be understood as within the scope of my invention that it may be employed, should occasion arise, for rendering other forms of timed service where a substantially similar manner of operation is required.

At the present time an advantageous particular field of utility of the timed service coin controlled device of my invention is for the convenient making of installment payments by the purchaser on the purchase price of a gas-using appliance, such as a gas range, for example; and also to facilitate the convenient making of collections by a representative of the dealer who has sold such an appliance subject to such payments. Such payments, to be effected by the coin controlled operation of the device of my invention, may be made at convenient periods. The particular embodiments of my invention disclosed herein are designed to provide service over a twenty-four hour period, although so far as the scope of my invention is concerned such period of timed functioning to provide service could be either for a longer or shorter interval of time, as may be desired for particular installations or conditions of service.

The capacity of the coin receptacle within the enclosing casing may of course be substantially anything desired, depending upon the convenience of making collections, which, merely for example, could be weekly, more or less, or at other regular or irregular periods. In carrying out my invention, the outer casing, which houses the operating mechanism of the device and also contains the collection of deposited coins, is not only securely locked but is especially devised and

constructed in a manner so as to prevent access thereto by tampering.

The coin controlled timed service device of my invention may be easily connected into the supply pipe leading to a gas range or other gas-using appliance. The coin controlled operating mechanism of the timed service device itself embodies a gas service valve which is normally closed and which is opened by the coin controlled mechanism when a coin controlled operation of such device is initiated, there being no other way of opening this valve. At the end of the predetermined period of service, this valve is automatically closed by the functioning of the timing feature of the device of my invention. The service provided, such as the flow of a supply of combustible gas, will then be automatically discontinued until another similar coin controlled operation is effected.

In one desirable embodiment of my invention disclosed herein, the service provided may be rendered continuous or without intermission merely by keeping the device supplied with coins in advance so that it will not run empty in that respect. In all of the herein disclosed examples of my invention, a plurality of coins may be safely inserted in advance, up to the capacity of the device in that respect, to be subsequently used in successive coin controlled operations of the device. Also it might be here noted that in each of the particular embodiments of my invention disclosed herein the coin controlled timing operation of the mechanism is effected by means of an energy storing device which is shown as a spring of the volute type, which of course requires winding, for driving a clock mechanism by which the timing is effected.

My invention includes various features of construction and combinations of parts, as will appear from the following description, with reference to the accompanying drawings, and as pointed out in the appended claims.

In order to enable a quicker grasping and clearer comprehension of my invention and of the several constructions shown in the drawings for carrying it out, it will here be noted in a preliminary way that: the first five sheets of the drawings, having thereon Figures 1 to 15 inclusive, illustrate one practical embodiment of the device of my invention; sheet six, with Figures 16 and 17, shows a somewhat different practical embodiment; sheets seven and eight, containing Figures 18 to 21 inclusive, show another form of my invention which embodies desirable improvements and simplification, Figure 20 showing a

variation in construction as compared with Figures 18 and 19; while sheet nine, carrying Figures 22 to 26 inclusive, illustrates a desirable improved construction over that shown in Figure 5 21 on sheet eight.

More particular reference will now be had to the accompanying drawings, in which similar parts are designated by similar reference numerals, and following a particular description of the 10 illustrated constructions, the invention will be pointed out in claims.

Figure 1 is a perspective view of a complete timed service coin controlled device in which one form of my invention is embodied.

15 Figure 2 is a front-to-rear vertical section of the casing only as viewed from the right in Figure 1, with dash lines indicating the open position of the swinging bottom closure or door.

Figure 3 is a horizontal section on the line 20 3-3 of Figure 2.

Figure 4 is a front elevation of the casing back together with the rear portion of the opened bottom closure, the outer part of the casing comprising the front, sides and top having been 25 removed.

30 Figure 5 is an enlarged front view in vertical section substantially on the zig-zag line 5-5 of Figure 6, showing the operating mechanism, in its normal condition of rest, mostly in front elevation but partly broken away, of the embodiment of my invention which is indicated in general in Figure 1, broken lines indicating the open position of the bottom closure of the casing.

35 Figure 6 is a vertical section on the zig-zag line 6-6 of Figure 5, broken lines indicating the bottom closure as partly open.

Figure 7 is a rear elevation of the operating mechanism shown as removed from the casing, with some of the hidden parts shown in broken 40 lines and with other parts in vertical section.

45 Figure 8 is for the most part an edge elevation of the rear mechanism-supporting plate together with parts of the mechanism carried thereby as viewed from the right and indicated by the line 8-8 in Figure 7.

Figure 9 is a partial horizontal section on the line 9-9 of Figure 7.

50 Figure 10 is a rear elevation similar to Figure 7, but showing the operating parts at an intermediate position of their operation.

Figure 11 is a partial horizontal section on the line 11-11 of Figure 10.

Figure 12 is a partial elevation as viewed from the left in the lower part of Figure 10.

55 Figure 13 is a horizontal section on the line 13-13 of Figure 5, with parts broken out and other parts omitted.

Figure 14 is a disassembled rear perspective view of a number of directly associated co-operating parts of the mechanism.

Figure 15 is a similar front perspective view of other parts of the mechanism.

Figure 16 is a front elevation in general similar to Figure 5, but showing a modified embodiment 65 of my invention.

Figure 17 is a partial side elevation as viewed from the right in Figure 16.

Figure 18 is a partial front elevation in general similar to Figure 5, showing a further modified 70 form of my invention.

Figure 19 is a side elevation as viewed from the right in Figure 18.

Figure 20 is a front elevation similar to Figure 18, showing a modification of the construction 75 illustrated in Figures 18 and 19.

Figure 21 is a rear elevation as viewed from the rear in Figure 18 and from the right in Figure 19.

Figure 22 is a rear elevation similar to Figure 21, but illustrating another modified embodiment 80 of my invention.

Figure 23 is an edge or side elevation as viewed from the right in Figure 22.

Figure 24 is a partial horizontal section on the line 24-24 of Figure 22.

Figure 25 is a similar view showing the manner of operation in moving the last coin when there is no other coin in the coin chute.

Figure 26 is a rear perspective view of the coin pusher.

With further particular reference to the accompanying drawings, the essentially related but specifically more or less different forms or variant embodiments of the timed service coin controlled device of my invention which are illustrated in the drawings will now be particularly described in the above noted successive order in which they appear in the drawings. The several forms of the illustrated device are constructed throughout of suitable metal.

The protective outer casing has a strong back plate 1. A casing cover part 2, which may be desirably formed in one piece, as shown in the drawings, comprises a front together with opposite sides and a top. This casing cover part 105 2 telescopes over the edges of the back plate 1 at the top and sides. Within the casing the top of the part 2 fixedly carries a catch strip 3 which engages downwardly behind a keeper strip 4 fixed on the back plate 1. Thus the top of the outer casing part 2 may be securely locked 110 to the top of the back plate 1 merely by moving it inwardly and downwardly. A casing bottom 5 is telescopically received within the casing walls formed by its back 1 and outer cover part 2. This 115 bottom 5 is hinged at 5A along its rear edge to open downwardly and rearwardly and may swing on a pintle pin 6 which is entirely within the casing and which therefore cannot be removed. One of the knuckles of this hinge is formed on the bottom 5 and the other may be formed on 120 the lower edge of the back plate 1. An inclined strip 7 which is fixedly secured to the casing back 1 within the casing, prevents the accidental lodging of coins on the hinge. In the casing 125 construction shown in the drawings, the front cover part 2 is further secured in place by means of lugs 8, 8 thereon, with downwardly headed screws 9, 9 passing upwardly through these lugs and screwed into anchor lugs 10, 10 which are 130 fixed on the back plate 1.

The casing bottom 5 is desirably formed in one piece, as shown, to include side walls and a front wall, these walls being shown as narrow, with the edges of the side walls inclined upwardly 135 from the rear. The bottom 5 is provided with a keeper lug 11 which is shown as struck inwardly from the upper margin of its front wall. The lower margin of the front wall of the casing cover part 2 carries a suitable lock 12 which is fixed thereon against removal from the outside by means of an inner collar 13. A swinging bolt or catch 14 of this lock terminates in a hook lug which in its locking position engages beneath the keeper lug 11 of the closed bottom 5, as shown in Figures 2 and 3. Combined supporting and spacing studs or lugs 15, 15, shown as six in number, are fixed on the casing back plate 1 at the inner side thereof. The operating mechanism is supported by means of these studs 15, 15 as will presently appear.

It is to be noted that the above described enclosing casing has no outwardly exposed screws, and there is no way of obtaining unauthorized access to the interior of the locked casing. It will be noted that the lock 12 not only locks the hinged bottom 5 but also locks the casing cover part 2 in place. Accumulated coins may be emptied out merely by unlocking the bottom 5, which forms a receptacle for these coins. It is to be understood that substantially the same casing construction is employed in the variant illustrated forms of the device of my invention. A main frame plate 16 of the operating mechanism is secured on the front ends of the casing studs 15 by means of screws 17, 17. A gas chamber 18, which is a valve chamber or valve body, having a front closure or cover plate 19, is fixedly mounted on the lower part of the main plate 16 at the front thereof by means of interposed spacers 20, 20. The valve chamber 18 is connected into a gas supply pipe having an induction section 21 at the left and an eduction section 22 at the right which pass snugly through the side walls of the casing part 2. The pipe section 21 is screwed into or otherwise secured to a tubular boss 23 on one side of the chamber 18 and the pipe section 22 is similarly secured in a similar tubular boss 24 on the other side of this chamber.

The main plate 16 at its back has a vertical rearwardly slotted flat coin chute 25 fixed thereto. The upper end of this coin chute registers with a transverse coin slot 26 in the top of the casing part 2 and is closed at its lower end by the upper edge of a horizontal plate 27 which provides a support for a first or lowermost coin 28 (Figures 6, 7, 9, 10 and 12) which has descended flatwise through the coin chute. As will hereinafter clearly appear, as many coins as desired may be inserted at any time until the coin chute 25 is filled.

In the particular construction now being described, a horizontally elongated tubular boss 29 is fixed on the left hand edge of the main plate 16 in line with the position of the coin 28 and extends snugly through the casing part 2. An outwardly headed coin-pusher stem 30 slidably telescopes into the boss or sleeve 29 and normally projects therefrom to the extent shown in Figures 1 and 7. A spring-winding stem or shaft 31 projects snugly but rotatably through the front wall of the casing cover part 2.

A mechanism frame surmounting the valve chamber 18 has front and rear plates 32 and 33 which are tied together by a plurality of spacers 34, 34. The spring-winding shaft 31 is journaled in these frame plates 32 and 33. This mechanism frame is surmounted by a top frame or auxiliary frame for other parts of the operating mechanism, more particularly for the clockwork relating to the functioning of the timing feature of the device of my invention. This auxiliary frame has front and rear plates 35 and 36 which are tied together by a plurality of spacers 37, 37.

The valve chamber 18, in alignment with its tubular outer boss 23, is provided with a tubular internal gas-supplying boss or nipple 38 the inwardly projecting end of which forms a valve seat, against which a movable valve member 39 is normally seated in closed position, to be moved away therefrom to an open position. It will be noted that this valve member has through it a small aperture 40, which in the closed position of this valve member will provide a sufficient flow of the combustible gas to sustain the flame of a

pilot burner only. The valve member 39 is pivotally carried, for slight rocking movement, by means of a pivot pin 41, on the upper end portion of an upstanding valve arm 42. The valve arm 42 is fixed upon a rocking valve-operating shaft 43 which extends horizontally from front to rear in the lower part of the valve chamber 18. The front end of this valve shaft is journaled in a bearing 44 carried by the front cover plate 19. This shaft is further journaled in a bearing 45 within the chamber 19 beyond which it extends rearwardly through and beyond a packing gland element 46. A valve-operating lever arm 47 is fixed upon the outer end of the valve shaft 43 at the rear of the valve chamber 18 and normally extends upwardly and at an inclination towards the right, as viewed from the front in Figure 5.

The coin-pusher stem 30, the inner end portion of which is tubular, is fixed upon the outer end of a coin-pushing plunger 48. A coiled thrust spring 49 acts between shoulders formed respectively in the boss 29 and the stem 30 for urging the coin plunger 48 to its outer position. This plunger 48 is shown as of rectangular shape in cross section (Figures 8 and 14). Its longitudinal movement is limited by means of a stop pin 50 carried by this plunger 48 and projecting from the front side thereof beyond the front face of the main frame plate 16 through a combined limiting and guide slot 51 in the latter (Figures 5, 7, 8, 9 and 11).

The coin-moving plunger 48 is normally locked at its outward position by means of a latch lever 52 pivoted at 53 on the main plate 16 at the front face of the latter and extending towards the left, as viewed from the front in Figures 5 and 15. This latch 52 is notched on its upper edge at its free end to provide a stop shoulder 54 and limiting finger 55. The projecting end portion of the stop pin 50 normally abuts against the shoulder 54 with the limiting finger 55 of the latch lever 52 in engagement with the lower side of this stop pin. This latch lever 52 has formed thereon a forwardly extending and upwardly projecting substantially U-shaped lug portion 56 which constitutes an actuating member thereof. A leaf spring 57 engaging with the lower side of its member 56 presses the latch lever 52 upwardly to its above noted locking position, this spring 57 being mounted on the main plate 16 at the front thereof (Figures 5, 6 and 15).

It is thought that the rest of this particular description can be more clearly and concisely couched in terms relating largely to the manner of operation of the coacting parts of the operating mechanism of the coin controlled timed service device of my invention, as to the embodiment thereof now being described.

Some preliminary information of a general nature seems advisable at this point. For opening the gas valve 39 and starting the timing operation of the clockwork mechanism by which this valve is eventually closed at the end of the predetermined period of service, the mechanism then automatically resetting itself in normal condition for the next succeeding coin controlled operation, it is advisable to proceed substantially as follows: First, insert one or more coins through the coin slot 26. The device of my invention will use but one coin, such as 28, at a time for each complete operation, the remaining coins in the coin chute 25 being held in reserve for successive use at subsequent operations of such device. Next, the spring-winding shaft 31 should

be rotated in a counter-clockwise direction for storing resilient operating energy. This spring-winding rotation of the winding stem 31 also unlocks the coin-pushing plunger 48, which then may be pushed inward, thereby moving the coin 28 from its position shown in Figure 7 to the position shown in Figure 10. This movement of the coin 28 immediately causes both the opening of the gas valve 39 and the beginning of the timing operation.

It may be here further noted that this particular embodiment of my invention has what in effect amounts to two geared-together and otherwise interconnected operating mechanisms, each of which has its own energy-storing operating spring, both of these springs being wound by means of the single winding shaft 31. One of these mechanisms operates the gas valve 39 in its opening and closing movements and the other mechanism is a timing clock in control of the closing of this valve. There is also what may be designated as the coin controlled mechanism, which is interconnected in co-operating relation with both of the above noted operating mechanisms. Thus there is produced a unitary co-organization of co-operating parts and features in the coin controlled timed service device of my invention.

In this particular embodiment of my invention, when the unlocked coin-moving plunger 48 is pushed inward, for initiating a coin controlled operation, a lug 58 fixed on the upper side thereof adjacent its forward face at first moves idly in a corner groove 59 provided in a slideable coin guard stop 60, until the lug 58 reaches and abuts against the end of this groove 59, whereupon the coin stop 60 will be moved inward by the coin plunger 48 (Figures 7, 8, 9, 10 and 14). This inward movement of the coin guard 60 projects its inwardly and downwardly sloping inner end into the coin chute 25, which is provided with a clearance notch 61 for this guard 60 (Figures 6, 7 and 10). This prevents the descent of a second coin immediately after the coin plunger 48 has automatically returned to its outer normal position.

This coin guard 60 slides in a guideway provided by a small bracket 62 which is secured on the rear face of the main frame plate 16. This guard slide 60 is urged outwardly to its normal ineffective position by a leaf spring 63 anchored at its upper end to the bracket 62 and engaging at its lower free end in a notch 64 in the top of the slide 60. When this coin guard slide 60 is pushed to its inner position, as above described, it is held against return movement by a dog or pawl 65 having at its upper end a pivot 66 on the bracket 62. From its pivot 66 the pawl 65 inclines inwardly and has a V-shaped lower end which then has locking engagement in a V-notch 67 in the top of the slide 60. The pawl 65 is pressed to its engaging position by a leaf spring 68, anchored at its upper end to the bracket 62 and engaging with a rearwardly turned ear or lug 69 on the pawl 65. At its outward edge this pawl 65 is shown as provided with another similar lug or ear 70 which is utilized for releasing the pawl 65, for the next succeeding coin controlled operation, through the operation of parts to be described later. It will be noted that the top of the guideway provided by the bracket 62 has through it a slot 71 for accommodating the guard-retracting spring 63 and the locking pawl 65.

Below the lower end of the rearwardly grooved

main plate of the coin chute 25, the main frame plate 16 has an outwardly inclined lug 72 struck rearwardly therefrom which directs the outer edge portion of the coin 28 rearwardly outwards (Figure 9). The inner edge of this coin 28, which is in its right hand edge as viewed in Figures 7 and 9, is similarly directed rearwardly away from the frame plate 16 by the transversely upwardly wedge-shaped end portion 73 of a coin ejector slide 74 in the normal retracted position of the latter. This ejector 74 is immediately beneath the coin-moving plunger 48 and is guided together therewith but independently thereof in a slideway provided by the upper portion of a small bracket 75 adjacently below the above noted bracket 62 and similarly secured on the rear face of the main frame plate 16. The coin-pushing end portion of the plunger 48 is cut away at 76 (Figures 9 and 14) along its side next to the main frame plate 16 in order to permit this plunger 48, as it moves the coin 28, to travel freely past the upwardly projecting coin-deflecting wedge 73 of the ejector 74. The ejector 74 is provided at the rear with a longitudinal taper face 77 which extends from the vertical transverse wedge 73, and provides for the coin-ejecting end of the latter being deflected into line with the coin, by the inclined lug 72, in the coin-ejecting movement of the ejector 74, as shown in Figure 11.

As above noted and as will presently be described in detail, the coin plunger 48 only moves the coin 28 far enough to inaugurate the valve-opening and timing operations of these respective mechanisms; whereas, as will hereinafter be described, the timing mechanism operates the ejector 74 to move the coin 28 farther and effect its discharge. The coin-ejecting operation, after it has ended, is illustrated in Figures 10, 11 and 12. In its ejecting movement, the lower edge of the coin 28 slides along the top of a ledge 79 formed on the rear face of a plate 80 which is secured on the rear face of the main frame plate 16 at its left margin beyond the coin chute 25, as viewed from the rear in Figures 7 and 10. Just before the coin-ejecting movement of the coin ejector 74 is completed, the lower edge of the outwardly moving coin 28 is crowded off the ledge 79 by an inclined lug or tongue 81 which is struck back from the plate 80, and the discharged coin will drop upon the casing bottom 5. The coin 28 will be discharged or released substantially at its position shown in Figures 10 and 12, but the ejector 74 will idly continue its advancing movement for a short distance, as is shown in Figures 10 and 11. The rear face of the coin ejector 74 has therein a deep vertical rectangular notch 82, while opposite this notch the slideway portion of the guide bracket 75 has through it a longitudinally extending arcuate slot 83, through which the coin ejector 74, by means of its notch 82, may be actuated in each direction of its movement.

Through the operation of means to be described later, the timing mechanism or clock, which normally is not running, is started by the coin plunger 48 pushing a coin, such as 28, from the position thereof shown in Figure 7 almost to the position of this coin shown in Figure 10, and at the end of the period of service, which in the present instance is twenty-four hours, the clock is automatically stopped. The clock mechanism includes a timing wheel 84, shown as a large gear wheel, which is normally stationary but which while the clock is running makes one complete rota-

tion and again comes to rest with the stopping of the clock. This 24-hour timing wheel is thus rotated in a right hand or clockwise direction as viewed from the front in Figure 5 and in a left hand or counter-clockwise direction as viewed from the rear in Figures 7 and 10. This wheel 84 carries a rearwardly projecting timing pin 85, the stationary normal position of which is shown in Figures 5, 6, 7 and 13, while in Figure 10 this pin 85 has not yet quite reached such normal position.

A rather long and large substantially L-shaped lever arm 86 is pivoted at its upper end, by means of a stud 87, at the rear of and in spaced relation from the main frame plate 16. This lever arm 86 extends downward along the right margin of the plate 16, as viewed from the rear in Figures 7 and 10, and has a lower finger projecting transversely at the rear of the lower end portion of the coin chute 25, the normal stationary position of this lever arm 87 appearing in Figure 7 and its operated position in Figure 10. The lever arm 86 is rigidly provided with a laterally bent or offset inwardly projecting actuating arm 88 the inner free end portion of which is disposed at the rear of the timed 24-hour wheel 84 in the path of its pin 85. The lever arm 86 is urged towards and normally retained at its retracted position (Figure 7) by a strong spring 89.

In the construction shown in the drawings, the 24-hour timing wheel 84 will make nearly or approximately $\frac{3}{4}$ of a rotation, as is evident from Figure 7, before its pin 85 will come into engagement with and begin to lift the actuating arm 88 of the lever arm 86. Obviously this will take place after about eighteen hours. This pin 85 then will slowly rock the lever arm 86 from the position shown in Figure 7 substantially to the position shown in Figure 10. In the further rotation of the wheel 84, from the position of its timing pin 85 shown in Figure 10 to that shown in Figure 7, this pin passes beyond the end of and releases the actuating arm 88 of the lever 86, whereupon the spring 89 immediately quickly retracts or snaps the lever 86 back to its normal position (Figure 7).

As the lever 86 is swung by the 24-hour wheel 84 a lug 90 thereon, which projects therefrom towards the main frame plate 16, abuts against the lug 70 of the pawl 65 and raises the locking end of the latter out of the notch 67 in the coin stop 60, whereupon the latter is moved by its spring 63 to its outer position shown in the drawings, thereby clearing the coin chute 25 for the next following coin, which can then descend into line with the inner end of the coin-moving plunger 48, which has been automatically returned to its outer position by its spring 49 and there automatically locked by the upwardly spring-pressed latch lever 52, along the top of which the stop pin 50 of the plunger 48 moves as the latter is retracted. The lever 86 carries another similarly projecting lug 91 which passes through the slot 83 in the bracket 75 and engages in the notch 32 of the coin ejector 74. Thus the ejector 74 partakes of the movement of the lever 86 in each direction of the movement of the latter. The timed movement of the ejector 74 will cause the end of its wedge-shaped portion 73 to discharge the coin 28 at substantially the expiration of nineteen hours, in the construction shown.

The hereinbefore noted valve-operating mechanism for the gas valve 39 has a power-providing driving spring 92 of the convolute or clock type (Figure 13) which surrounds and is mounted

upon the winding shaft 31. The outer end of this spring is connected to a spring drum or housing 93. The drum 93 is fixed upon an internal boss or hub 94 which is pinned to or otherwise fixed upon the winding shaft 31. The inner end 80 of the spring 92 is connected to a sleeve or collar 95 which is rotatively loose on the winding shaft 31 and which at its outer or front end rigidly carries a gear 96. When the winding shaft 31 is rotated in a left hand or counter-clockwise direction for winding the spring 92 it carries the spring drum 93 with it, so that thus the spring 92 is wound from its outer end by means of the drum 93. At its back the spring drum 93 has mounted thereon and carries a stop pawl 97 and its spring 98. In the winding operation the pawl 97 moves over the teeth of a ratchet wheel 99 which is fixedly secured to a gear 100 which is immediately at the back of this ratchet wheel (Figures 5, 6 and 13). Both the ratchet wheel 99 and the gear 100 are rotatively loose on the winding shaft 31, this gear together with the ratchet wheel being at this time locked by means to be described later.

As the spring 92 becomes wound during the 100 winding operation, its inner end transmits torque and rotation, in the winding direction, to the front gear 96. This gear 96 meshes with an upper gear 101 which is a winding gear for a driving spring or main spring 102 for the timing 105 mechanism or clock (Figure 6). Thus both of the springs 92 and 102 are coupled together to be jointly wound up by the winding shaft 31 and whereby both of these springs may jointly release their stored energy as they unwind, in 110 driving the clock mechanism.

At its rear end, beyond the frame plate 33, the winding shaft 31 has fixed thereon a pinion 103 which meshes with a gear 104 which has centrally fixed thereto at the front thereof a single-rise wiper cam 105, so that the cam 105 will be rotated by the gear 104, the latter being rotated by the pinion 103 and the spring-winding shaft 31 during the spring-winding operation, later to be returned in a reverse direction, by the operation of means presently to be described.

The cam 105 is so timed that, in the spring-winding operation, when the operating mechanism spring 92 and the clock spring 102 have been fully wound, this cam 105 will have been 125 moved into engagement with the top of the lug 56. This cam, acting upon the lug 56, presses down the latch lever 52 and holds it down, with the cam 105 then stationary, at the completion of the winding of the springs 92 and 102. Thus 130 the coin-moving plunger 48 is in an unlocked condition, and the lowermost coin 28 may be pushed from its first position shown in Figures 7 and 9 approximately to its position shown in Figure 10, by the coin plunger 48 when the latter 135 is manually operated. When the coin 28 is thus moved, its upper edge engages beneath and lifts a cam end 106 of a lug 107 which projects rearwardly from the end of a coin-operated lever 108. The adjacent portion of the coin chute 25 140 is cut out or notched at 109 to provide clearance for the cam end 106 which passes through an opening 110 in the main frame plate 16. This lever 108 extends transversely in spaced relation at the front of the frame plate 16 and at its other end is pivoted or fulcrumed thereon at 111. This coin lever 108 has a forwardly projecting operating lug 112, shown as struck out therefrom. This lug 112 extends beyond and has clearance in a notch 113 in the lower edge of the rear 145

frame plate 33 of the operating mechanism (Figures 5 and 13).

The lifting of the lever 108 by the coin 28 immediately starts the wound timing mechanism 5 or clock. This clock has a usual escapement wheel 114 controlled by a usual escapement lever 115. This escapement lever is normally engaged and held against operating movement by the inner end of a two-armed controlling lever 116 having an intermediate fulcrum pivot 117. The outer end of this lever 116 has a cushioning connection to the coin lever 108, by which this controlling lever is operated, and such connection shown in the drawings will be described. The 10 coin lever lug 107 carries a post 118 to which is pivoted the lower end of a wire or small rod 119 the upper end of which is fixed in the lower end of a tube 120. A guide wire or rod 121 pivoted to the controlling lever 116 telescopes 15 into the upper end of the tube 120 for free relative sliding movement. The end of this lever 116 and the lower end portion of the tube 120 are connected together by a light double-acting or push-and-pull coiled spring 122. When the coin lever 108 is moved downward to its normal position, by means described later, it pulls upon the 20 spring 122 which results in a cushioning or yielding contact of the inner end of the controlling lever with the escapement lever, which stops the clock without doing any harm to its escapement. When the coin lever is moved upward, as above 25 described, the inner end of the controlling lever 116 is moved away from the escapement lever 115 by an upward push imparted to the spring 122, to start the clock at the beginning of the timing 30 operation.

In the construction shown in the drawings, after the coin 28 has been discharged, as above 35 described, the coin lever 108 is held at its raised position by the upper edge of the end portion of the transverse finger of the L-shaped lever 86 which moves in engagement with the lower side of the cam lug 106 and so remains until this lever 86 is finally retracted at the termination 40 of the timed period of service, so that thereby in the meantime the timing clock is kept running, in the manner above noted. Just as soon as the coin lever 108 is lifted by the advancing coin 45 28, it not only starts the timing clock running, as above described, but its operating lug 112 lifts a starting lever or pawl arm 123 of the valve-operating mechanism, by which the gas supply 50 valve 39 is immediately opened with a quick motion, by power transmitted from the wound operating spring 92, through intervening operating 55 connections now to be described.

This pawl arm 123 normally, or in the idle condition of the device of my invention shown in Figures 5 to 9 inclusive and 13, abuts downwardly 60 against a stop pin or stud 124 which projects forwardly from the front of the rearward mechanism frame plate 33, with the coin lever lug 112 then close beneath the pawl arm 123 (Figure 5). This starting pawl 123 is fixed upon a rock shaft 125 upon which there is also fixed an upstanding tail arm 126 to which there is connected a retractile spring 127 the other end of which is anchored to one of the frame spacers 34, in position for resiliently holding the starting pawl 123 65 down against its stop pin 124. Thus the coin lever 108 raises the starting pawl 123 against the force of its spring 127, which in turn urges this coin lever downward toward its normal position.

The gear 100, as above described, has torque 70 applied thereto by the wound spring 92, through

the drum 93, pawl 97 and ratchet wheel 99, this torque being in a clockwise direction as viewed from the front and indicated by the arrow in Figure 5. This gear 100 meshes with a smaller gear 128 which is fixed upon a rotatable shaft 129 (Figures 5, 6 and 13). Also fixed upon this shaft is a pawl-controlled controlling disc 130. This disc 130 has two diametrically opposite abutments 131 and 132 projecting beyond its rear face, these abutments being shown as struck out therefrom in the form of circumferential tongues. These abutments are radially out of circumferential alignment, with the normally lower abutment 131 farther from the center than the other abutment 132. The free end of the pawl arm 123 normally is abutted by the lower and outermost abutment 131, as shown in Figure 5. This pawl arm 123 thus locks the ratchet wheel 99 to prevent free unwinding of the spring 92.

When this pawl arm 123 is lifted by the coin lever 108, as above described, its free end is raised into the path of the upper or inner abutment 132, the lower or outer abutment 131 then being set free. Thereupon the controlling disc 130 immediately quickly makes a one-half turn 100 counterclockwise rotation, as indicated by the arrow in Figure 5, by reason of the torque transmitted to this disc 130 through the gear 128 from the gear 100 under the impulse of the wound spring 92. At the end of such half-turn movement the further rotation of the controlling disc 130 is stopped by its inner abutment abutting against the raised free end of the starting pawl 123.

A valve-operating crank disc 133 is fixed upon 110 the rear end of the rotatable shaft 129 in the space between the rear frame plate 33 of the operating mechanism and the main frame plate 16. This disc 133 carries a crank pin 134, shown in Figures 5, 6 and 13 as above and in vertical alignment with the rotatable shaft 129. The crank pin 134 pivotally carries the upper end of a valve-operating link 135 which normally extends downwardly and at a slight inclination towards the right, as viewed from the front in Figure 5. 120 The lower end of this link 135 carries a pivot pin 136 by which it is pivotally connected to the end of the valve-operating lever arm 47, for thereby first opening and then finally closing the gas supply valve 39. This pin 136 works in the lower and 125 right hand end of a transverse slot 137 in the lever arm 47, where it is yieldingly maintained by the free end of a leaf spring 138 the other end of which is anchored to the valve-operating lever arm 47. This spring connection between the 130 lever arm 47 and its operating link 135 will cushion the valve 39 or seat it in a yieldable manner in its closing movement; also in the valve-opening movement of the crank disc 133 it provides, in the construction shown, for the easy passage of the link 135 beyond the slight dead center relative to the axis of the shaft 129, as the latter rotates the crank disc 133.

It is manifest from the preceding description that when the controlling disc 130 is released by its starting pawl 123, then the crank disc 133 will be quickly rotated therewith, through a half turn, thereby bringing the crank pin 134 to a diametrically opposite lower position, thus quickly opening the gas supply valve 39 by means of its 140 swinging arm 42. It is obvious that the gas valve 39 is thus opened by power derived from the operating spring 92. During this part of the operation, the outwardly returned coin plunger 48 will be again locked, by reason of its unlocking 145 75 through

cam 105 moving away from the lug 56 of the latch lever 52, due to the rotation of the winding shaft 31. Accidental or incidental reverse movement, from any cause whatever, of the above described 5 interconnected valve-operating parts, is positively prevented by means of a back-lash pawl 139 having its free end engaged at an inclination between the teeth of the gear 128, so as thereby to provide for its forward or operating 10 rotation while locking it against backward or reverse rotation. This back-lash pawl is loosely pivoted on the rock shaft 125 and is constantly pressed downwardly to its engaging position with the gear 128 by means of a small retractile spring 15 140 connected thereto and anchored to a pin 141. It will be noted that the back lash pawl 139 locks the valve 39 against opening movement.

It has been hereinbefore noted that throughout the period of service, in this instance twenty-four hours, the coin-operated lever 108 is at first held up by the coin 28, and then, after this coin has been ejected, this coin lever 108 is still held up, during the remainder of the period of service, by the end portion of the finger of the 20 long L-shaped lever arm 86, whereby the timing clock continues to run. It is now to be noted that during the entire 24-hour service period, this coin lever 108 holds the starting pawl 123 up in opposition to the force of its spring 127 and in abutting engagement with the second or radially inner controlling disc abutment 132, so that thereby the service valve 39 is held open. When the L-shaped lever arm 86 is released by the timing pin 85 of the 24-hour clock wheel 84, as hereinbefore described, then the spring 127 of the starting pawl 123 will immediately shift this pawl downward against its abutment stud or stop pin 124. Thus the pawl arm 123 is moved out of engagement with and releases the radially inner 30 controlling disc abutment 132 and is moved into the path of the outer abutment 131. The controlling disc 130, being again set free, is immediately given another quick half-turn rotation, in the same direction as before, by the mechanism 40 spring 92, where it is stopped by its abutment 131 abutting against the end of the pawl arm 123, this disc then having resumed its original normal position.

This last half-turn rotative movement of the 50 crank disc 133 brings its valve-operating crank pin 134 from its lower or service position back to its uppermost normal position, shown in Figures 5, 6 and 13. This movement of the crank pin 134 draws upwardly upon the valve-operating link 55 135, thereby swinging the valve-operating lever 47 upwardly and quickly closing the gas supply valve 39 by means of the rocking shaft 43 and its upstanding valve-carrying arm 42. This valve 39 is thus closed, with a quick movement, by power transmitted from the mechanism-operating 60 spring 92, through intervening operating connections already described.

When the coin lever 108 has been released, at the end of the period of service, as above described, it not only tends to move downward by its own weight but it is rather strongly pressed downward by the starting pawl 123, by force transmitted from the rather strong spring 127 of the latter. This downward movement of the 70 coin lever 108 causes it to draw downward on the light spring 122, through which this coin lever 108 is operatively connected to the controlling lever 116, in a manner already described. The stretching force thus applied to this spring 122 75 consequently pulls downward upon the outer arm

of the controlling lever 126 and causes the free end of its inner arm to abut against the escapement lever 115 of the timing clock mechanism. This contacting engagement of the controlling lever 116 with the escapement lever 115 is sufficiently gentle not to damage the escapement and at the same time is strong enough to hold the escapement lever 115 against rocking operating movement, only very slight force being required for this purpose. Thus the timing clock is stopped at the termination of the 24-hour period of service, this result being initially effected by its own 24-hour timing wheel 84, as will be readily understood from the preceding description.

The further rotation of the winding shaft 31 during the valve-closing and clock-stopping operations just described results in the resetting of the timed cam 105 to its original normal position, so it will become effective at the next coin controlled operation for releasing the locked coin pushing plunger 48. When, at the end of the period of service, the timing pin 85 of the 24-hour clock wheel 84 releases the L-shaped lever arm 86, as hereinbefore described, the operation of the timing clock mechanism is stopped, the gas supply valve 39 is closed, and also the coin ejector 74 is retracted or reset; in fact, all parts of the entire mechanism are restored to their original or normal position and condition, preparatory to a subsequent similar coin controlled operation of the coin controlled timed service device of my invention.

It is believed that the construction and operation of this particular form of the coin controlled timed service device of my invention have now 110 been fully described.

It might be further noted that the timed cam 105, shown as operated by the intermeshed pinion 103 and gear 104, could be similarly operated by other means, within the scope of my invention. For example, by means of a Geneva movement similar to that commonly used on clocks. In such case, the pinion 103 would be replaced by the Geneva pin or stud element and the gear 104 by the Geneva toothed or gear element. This would result in a uniformly exact positioning of the cam 105. However, the construction shown in the drawings has been found to operate successfully in a practical manner.

In illustrating the modified forms of construction of the coin controlled timed service device of my invention shown in the accompanying drawings, parts of the mechanism which are the same or substantially the same are repeated only to the extent necessary for clearly indicating their connection and operating relation, thus avoiding unnecessary duplication in the drawings; and the description will proceed along similar lines, thereby contributing to both clarity and conciseness, the same reference numerals being used for the 125 repeated similar parts.

Reference will now be had to Figures 16 and 17 on sheet six of the drawings, illustrating a practically workable embodiment of the coin controlled timed service device of my invention having a modified form of the valve-operating mechanism. The timing mechanism or clock remains substantially the same as in the first illustrated and described construction, and similarly practically no change has been made in the coin controlled mechanism, although the interconnected relationship between the clock mechanism, valve-operating mechanism and coin controlled mechanism is somewhat different, by reason of the 140 differently constructed valve-operating mecha- 145 150

nism, which is now to be particularly described, together with its interconnected relation in the complete unitary coin controlled timed service device of my invention.

5 The gas supply valve 39 is shown as in its normally closed position. A valve-operating lever arm 142 is fixed upon the outer end of the rocking valve-operating shaft 43 and is shown as normally extending upwardly and at an inclination towards the left, as viewed in Figure 16. This lever arm 142 is shown as at the front of a mechanism frame plate 143 which corresponds in general with the main frame plate 16 in the previously described construction. In order to show the valve 39, together with its arm 42, at the inside of the valve chamber 18, the lower part of the frame plate 143, together with some other parts, is broken away in both Figures 16 and 17 and there indicated by broken lines, but the valve-operating lever arm 142 has been shown in full lines. The upper end of this lever arm 142 carries a projecting pin 144. This pin engages in a longitudinal slot 145 in the lower end of a valve-operating lever 146. This valve-operating lever 146 is fulcrumed to swing on the outer end portion of a stud 147 which projects forwardly from the frame plate 143. This fulcrum lever 146 is shown as a straight lever of the first order or class, having a long downwardly extending arm and a much shorter upstanding arm.

30 In this construction, the valve 39 is normally held in closed condition and when open is eventually again closed, for terminating the service, by means of torque which is constantly at all times applied to the valve-operating fulcrum lever 146 in a right hand or clockwise direction, as viewed in Figure 16. This torque and valve-operating driving power is derived from the usual main spring of the timing clock, such as the main spring 102 shown in Figure 6. This is accomplished through the intermediary of a gear train now to be described. This is a power-multiplying and correspondingly speed-reducing train of gearing which acts upon the upper end of the shorter upper arm of the valve-operating lever 146. During all of the time that the timing clock is running it rotates a gear wheel 148 in the clockwise direction indicated by the arrow in Figure 16. In the normal idle condition of the device the clock is not running but a torque impulse from its main spring is still applied in the same direction, to the then stationary gear wheel 148. This clock-operated gear wheel 148 is fixed upon the end of a rotatable shaft 149 journaled in a bearing 150 which projects from the back of the frame plate 143, and a pinion 151 is fixed upon the other end of this shaft 149 at the front of the frame plate 143.

60 A gear wheel 152 has a smaller gear or pinion 153 fixed thereto at the front thereof, and these two axially coupled gears 152 and 153 are loosely rotatively mounted on the fulcrum stud 147 of the valve-operating lever 146 between the latter and the frame plate 143. A fixedly axially coupled pair of idlers comprising a small gear 154 and a pinion 155 is loosely rotatively mounted upon a bearing stud 156 which projects forwardly from the frame plate 143, with the pinion 155 between this plate and the gear 154. This pair of idlers 154 and 155 operatively connects together the pinion 151, which is fixed upon the shaft 149, and the gear wheel 152, which with its coupled small gear 153 is loosely rotatable upon the pivot stud 147 of the valve-operating

fulcrum lever 146, the idler gear 154 meshing with the clock-connected pinion 151, and its coupled idler pinion 155 meshing with the loosely rotatable gear wheel 152 on the stud 147. If the gearing relation be traced, which may be done readily by the indications of the arrows, it will be found that the clock-operated gear wheel 148 transmits a torque impulse in the same rotative direction to the loosely mounted gear wheel 152 on the stud 147 and thus to its coupled small gear 153.

65 The short upper arm of the valve-operating lever 146 carries on its end a stud 157 which projects towards the frame plate 143. A small planetary gear 158 is loosely rotatively mounted on this stud 157 and meshes with the small gear 153, which is coupled to the larger gear 152. This planetary gear 158 is also an intermediary idler which engages or intermeshes with the lower side of the periphery of an upper gear wheel 159. This upper gear wheel 159 is fixed by means of an intermediate sleeve or collar 160, to a similar upper front gear wheel 161, for the unitary rotation of these two gear wheels as one, and with slight changes in the designing they could be merged into one. These two companion gears 159 and 161 together with their coupling sleeve 160 are loosely rotatable upon a stud shaft 162 which is fixed upon and extends forwardly from the frame plate 143. These coupled upper gears 159 and 161 may be considered as idlers, in the sense that they do not transmit motion.

70 In the normal idle condition of the device, in which all of the operating parts of its mechanism are stationary, the upper front gear wheel 161 is releasably locked by means of a locking lever 163 which is pivoted on the frame plate 143, at the right margin thereof, (Figure 16), by means of a pivot pin or stud 164 and is spaced forwardly from this plate by a boss 165. This locking lever 163 has a lateral arm the end of which extends just at the back of the lower portion of the upper front gear wheel 161, where the end of this arm is turned outward to form a locking lug 166 which is shown in full lines as engaged between two of the teeth of the gear 161 so that thereby this gear wheel 161 is locked against rotative movement in either direction. A retractile spring 167, shown as connected to an upstanding bell-crank tail arm of the locking lever 163, is anchored to the frame plate 143 by means of a stud 168 in position for urging the lug 166 into locking engagement with the teeth of the gear wheel 161. It is obvious that this spring 167 could be otherwise connected to the lever 163, for example, the lateral arm of this lever might be further extended towards the left (Figure 16) beyond the adjacent gears, with this spring 167 then connected to such extension and positioned to urge it upwardly.

75 The clock-operated gear wheel 148 is not in itself a timing wheel but is a power wheel for applying torque and transmitting rotation. Both this power gear 148 and the 24-hour timing gear 84 are similarly directly driven by the clock mechanism of the timing clock, (through suitable gearing connections not shown), so that thereby when the timing clock is running both of these gear wheels 84 and 148 will be rotated, and when the clock is stopped, which occurs at the end of the period of service, then both of these gear wheels, that is, the timing gear 84 and the power-transmitting gear 148, become stationary and remain so until the timing clock has been again started to run by initiating a subsequent coin controlled

operation of the mechanism of the device of my invention. In this particular mechanism now being described, the opening movement of the gas supply valve 39 takes place concomitantly with the starting of the timing clock, while the closing movement of this gas valve is transmitted to it directly from the timing clock mechanism while this timing clock is still running.

In the normal stationary idle position of all 10 of the operating parts of the mechanism, as shown in full lines in Figure 16, it is to be noted that the gas supply valve 39 is maintained in its closed position and in sealing relation with its seat on the end of the valve chamber boss or nipple 38 15 by means of pressure applied to this valve by the stopped timing clock, this pressure being derived from the main spring of the clock, such as the main spring 102 (Figure 6). It will be noted that this main spring is transmitting and applying torque in a right hand or clockwise direction to the small gear 153, through the above described interengaging gearing.

Since this small gear 153 is loose on the fulcrum stud 147 and not directly connected with the 20 valve-operating lever 146, which is also loosely pivoted on its fulcrum stud 147, it is obvious that the clockwise torque on the small gear 153 will directly transmit and apply torque in the opposite or counter-clockwise direction to the planet- 25 gear 158, as indicated by the arrow (Figure 16). Since this planetary gear 158 is in mesh with the locked upper gear wheel 159, it becomes evident that the counter-clockwise torque on the planetary gear 158 will exert a tendency to move 30 the upper end of the valve-operating lever 146 towards the right as viewed in Figure 16, thereby applying power-multiplying torque in a clockwise or valve-closing direction to the valve-operating lever 146, whereby the lower end of this lever 40 will be urged towards the left (Figure 16), for holding the gas supply valve 39 closed. The force of this applied power of the timing clock, for holding the valve 39 closed, is received and borne by the locked upper gear wheels 159 and 161, 45 as a thrust or strain thereon in a clockwise direction, as indicated by the arrow in Figure 16.

It will now be seen that the timing clock will be locked or blocked against running by reason of the above described locked condition of the 50 operating parts of the valve-operating mechanism, and that the timing clock will be thus restrained or locked against running so long as the two above described conditions are maintained, namely, that the locking lug 166 is in engagement with the teeth of the upper gear wheel 161, while at the same time the gas supply valve 39 is closed against its seat on the nipple 38. This represents the normal idle condition of this form 55 of the coin controlled timed service device of my invention. The interconnected parts of the device which operate under coin control for causing the gas supply valve 39 to be opened and for at the same time starting the timing clock to running, will now be described.

A coin-operated lever 169 is pivoted, at an intermediate point along its length, at the front of the frame plate 146, on a pivot stud 170 which is mounted on this frame plate. Although this coin lever 169 is variously bent in other respects, it is 60 shown as in effect constituting a substantially straight transversely extending lever of the first order or class. The end of the inner or left arm (Figure 16) of the coin-operated lever 169 is pivotally connected by a link 171 with the inner or left 65 end of the locking lever 163, which extends beyond

its locking lug 166. When the coin 28 is moved by the coin-pushing plunger 48, in the manner hereinbefore described with reference to Figures 1 to 15 inclusive, its upper edge similarly engages beneath and lifts the cam end 106, which in this instance is carried by the right hand end (Figure 16) of the coin-operated lever 169, where this cam end 106 similarly projects rearwardly beyond the rear face of the frame plate 143, through an opening 172 which corresponds with the opening 110 in the first described main frame plate 16.

The lifting of the cam end 106 of the coin-operated lever 169 by the advancing movement of the coin 28 draws downward upon the link 171 which pulls the locking lever 163 down against the force of its spring 167, thus shifting the locking lug 166 downward to a position in which it is free from the teeth of the upper gear wheel 161, which thereby releases or sets free both of the two coupled wheels 159 and 161. This operated position 90 of the locking lever 163, as well as also that of the coin-operated lever 169 is indicated by broken lines in Figure 16. It is to be here noted that neither of the coupled gears 159 and 161 has any operative connection with anything else excepting 95 the permanent engagement of the planetary pinion 158 with the one gear 159 and the releasable engagement of the locking lug 166 with the other gear 161.

It has already been noted that the timing clock 105 is prevented from running by the joint blocking or locking function of the closed valve 39 and the engaged locking lug 166, and in this embodiment of the invention the running of the timing clock is unrestricted and unhampered in any other way. 110 Accordingly it is evident that it is necessary to release only one of the two above noted jointly acting locks in order to permit the clock to run. Therefore the instant that the locking lug 166 releases the teeth of the upper front gear wheel 161, the previously wound timing clock will begin 115 running. The planetary gear 158 may now impart idle rotation to the intermeshed rear top gear wheel 159. The running of the timing clock will now impart idle rotation to all of the gears in the 120 above described train, beginning with the clock-driven gear wheel 148 and ending with the unlocked top front gear wheel 161. The directions of these idle rotations are indicated by the arrows in Figure 16.

It is also now to be noted that at this same above noted instant that the locking lug 166 has released the teeth of the upper front gear wheel 161, then the valve member 39 is released for free opening movement. That is because the released upper 130 rear gear wheel 159 now not only permits idle rotation of the planetary gear 158 but also permits free swinging valve-opening movement of the valve-operating lever 146, which of course will be towards the right in Figure 16 for the long lower arm of this lever. It should be obvious that such a swinging movement of the valve-operating lever 146 would only idly superimpose further idle rotation upon the coupled upper gear wheels 159 and 161 in addition to that idly transmitted by 135 the running clock, and in the same direction. Therefore the valve 39 is now free to be opened without hindrance.

Just as soon as the valve-operating lever 146 has been thus set free, the gas supply valve 39 is 145 immediately quickly and practically instantaneously opened by a stretched retractile spring 173, which is shown as extending transversely with its inner or left end (Figure 16) connected to the lower part of the valve-operating lever 146, while 150

the other or outer end of this spring is anchored to a stud 174 on the frame plate 143. The extent of the opening movement of the valve 39 and also of the swinging movement of the valve-operating lever 146 are limited by an abutment stud 175 on the frame plate 143, to be abutted by this lever. Broken lines in Figure 16 indicate the position of the valve-operating parts, from the valve arm 42 to the swinging lever 146 inclusive, in the open position of the gas supply valve 39.

It has already been noted that in this particular valve-operating mechanism, the closing movement of the gas supply valve 39 is transmitted to it directly from the timing mechanism of the clock while this clock continues to run. It might be here further noted, somewhat in advance, that this valve 39 is closed by a slow movement imparted to it during the terminal portion of the period of service, as will presently clearly appear. It has also been hereinbefore noted that this form of the coin controlled timed service device of my invention embodies a modified form of the valve-operating mechanism, while there has been substantially no change in the timing clock, nor in the coin controlled mechanism. The interconnected relation of parts and features for causing the closing of the gas supply valve 39, for terminating the service, will now be described.

It will be noted, as in the first described construction, that the 24-hour wheel 84 (which may have a different period if so desired), by means of its timing pin 85, operates a similar or corresponding downwardly extending lever arm 86, by means of its actuating arm 88. Similarly, this lever arm 86, by means of its lug 90, controls the operation of the coin stop 60, and also in a similar manner, by means of its lug 91, the coin ejector 74. However, with this particular lever arm 86, the transversely projecting lower finger portion, which was utilized in the first described construction, has now been omitted, by reason of the fact that its previous function is now performed by other elements and in a different manner, in accordance with this modified construction. In this latter construction, as in that first described, the coin 28 will be discharged by the ejector 74 substantially at the expiration of nineteen hours. However, in the present instance, since the finger of the lever arm 86 has been removed, there is now nothing to hold up the cam end 106 of the coin-operated lever 169, after the coin 28 has been ejected. While the changes in construction relate chiefly to the valve-operating mechanism, these changes involve further modification in operating parts, as has been noted.

As soon as the coin, such as 28, has been ejected from beneath the cam end 106, the force exerted by the stretched spring 167, acting upon the locking lever 163, not only immediately repositions the cam end 106 to its lower normal position, by rocking the coin-operated lever 169 through the link 171, but also at the same time moves the locking lug 166 of this locking lever 163 upward into locking engagement with the teeth of the upper front gear wheel 161. The locking of this wheel 161 of course locks its coupled mate 159, with which the planetary gear 158 is intermeshed. The gas supply valve 39 now being open, with its operating lever 146 at the broken line position shown in Figure 16, the timing clock will continue to run since this lever 146 is now free to swing in a clockwise valve-closing direction. The timing clock mechanism therefore immediately begins to close the valve 39, by acting through

the above described train of gearing in the direction still indicated by the arrows in Figure 16. In this valve-closing operation, the planetary gear 158 will walk or travel towards the right (Figure 16) over the teeth of the upper rear locked gear wheel 159. This obviously moves the short upper arm of the valve-closing lever 146 towards the right (Figure 16) while its lower long arm is swung towards the left, thereby moving the open valve 39 towards its closed position, shown in full lines in Figure 16.

The closing movement of the gas supply valve 39 is slow and gradual, by reason of the hereinbefore described speed-reducing power-multiplying functioning of the gear train, by which valve-closing movement is transmitted from the clock-operated gear 148 to the stud 157 on the upper end of the valve-operating lever 146. The valve 39 will thus be closed against its seat on the nipple 38 within about four or five hours time. This slow closing movement of the valve 39 is an advantage, since the consequent diminution in the flow of gas, which becomes noticeable only towards the very end of the period of service, serves as a reminder to apprise the user that another coin controlled operation is required, should a further supply of gas be desired at that time. Until close to the end of the period of service, which in this instance is twenty-four hours, but may be varied, the supply of gas will remain undiminished.

The modified construction shown in Figures 18, 19 and 21 is simple and economical while it is entirely effective, therefore I prefer this construction over the more complicated preceding forms.

The timing clock, when running, drives a 24-hour gear wheel 176 in a clockwise direction as seen in Figure 18. This wheel, on a thickened portion thereof, is peripherally provided with an annular groove 177 the bottom of which forms a nearly complete circular track, which is broken by a recess 178, the leading face of this recess being abrupt, while its trailing face is inclined. A branching three-armed operating lever 179 is pivotally fulcrumed on a stud 180, this stud being mounted on a plate 181 below and to the left (Figure 18) of the center of the 24-hour timing wheel 176, which is also supported on the plate by a journal pin 182. The operating lever 179 is biased or automatically urged to rock or move in a clockwise direction by a retractile biasing spring 183 having one of its ends pivoted to this lever below its pivot 180 and having its other end anchored to a stud 184 on the plate 181 towards the left from this lever.

This three-armed operating lever 179 has an upstanding arm 185 which inclines inwardly to the adjacent periphery of the wheel 176 and has an abrupt bill-shaped end which rides on the track formed by the groove 177. The free end of this arm 185 is normally seated in the recess 178 with its end adjacent the abrupt face of the latter, so as to ride up the inclined face of this recess onto the track 177 when the wheel 176 is rotated.

The operating lever 179 has a downwardly extending valve-operating arm 186, the lower end of which has a longitudinally slotted pivotal connection with a pin 187 on the upper end of an upstanding valve arm 188 which is fixed upon the valve shaft 43, whereby the gas supply valve 39 is normally maintained in its closed position by the spring 183, which also presses the upper lever 15

arm 185 against the track 177 and into its recess 178.

The operating lever 179 has an intermediate coin-operated arm 189 extending laterally towards the right (Figure 18) and thus forming a bell-crank lever with each of the arms 185 and 186. This coin-operated arm is provided with the same cam end 106 as in the previously described constructions, by which it may be similarly lifted 10 by a moving coin in the same manner. This arm also has a clock-controlling connection to the clock escapement for starting and stopping the clock similarly to the first described construction.

15 When a coin lifts this lever arm 189, the timing clock is immediately started to run, while at the same time the lower lever arm 186 operates to open the gas supply valve 39, and the end of the upstanding lever arm 185 is moved out 20 of the recess 178. When the used coin has been ejected from beneath the cam end 106 by the ejector 74, in the manner already described, the end of the upstanding arm 185 will then ride upon the track 177, the recess 178 having then 25 moved away from the end of this latter arm. Thus, after the coin has been discharged, the service valve 39 will still be held open and the clock will continue to run, while the clock continues to rotate the timing wheel 176.

30 When the timing wheel 176 has completed a single rotation, which occurs at the end of the predetermined period of service, which in this instance is twenty-four hours, the end of the upstanding lever arm 185, riding on the track at 35 the bottom of the groove 177, reaches the abrupt end face of the recess 178 and is impelled into this recess by the spring 183. This same action of the spring 183 instantly stops the timing clock, through the downward movement of the coin-operated arm 189, and also closes the gas supply valve 39 through the valve-closing movement, 40 towards the left (Figure 18), of the valve-operating lower lever arm 186.

The further slightly modified or variant construction shown in Figure 20 operates in substantially the same way as the construction just described with reference to Figures 18 and 19. In Figure 20, the valve shaft 43 has a normally upright valve arm 190 fixed thereon, the upper end 45 of which, by means of a pivot pin 191 and longitudinally slotted connection, is connected with the lower end of a normally vertical rocking controlling lever 192, which at an intermediate point along its length is fulcrumed on a pivot stud 193 mounted upon a supporting plate 194.

The upper end of the rocking lever 192 has a projecting rounded nose end or lug 195 which, with the gas supply valve 39 closed and the clock stopped, seats in a recess 196 in a circular track 197 on the periphery of a 24-hour gear wheel 198. A bell-crank lever having a transversely extending coin-operated arm 199 and an upper arm 200 is pivoted on a stud 201 on the plate 194, and has its upper arm 200 pivotally connected 50 with the upper arm of the rocking lever 192 by means of a link 202. The coin-operated arm of this bell-crank lever is urged downwardly by a valve-closing and clock-stopping spring 203.

55 The 24-hour timing wheel 176 shown in Figures 18 and 19 carries a timing pin 85A for co-operating with the actuating arm 88 of the long downwardly extending lever arm 86 in the manner hereinbefore described with reference to the similar timing pin 85. Also the 24-hour timing

wheel 198 shown in Figure 20 carries a corresponding timing pin 85B which operates in like manner. Figure 21 shows the lever arm 86 which belongs to the construction illustrated in Figures 18 and 19.

Figures 19 and 21 show advantageous improvements in the means for manually operating the coin-pushing plunger 48. The improvements in this feature may be equally well and similarly applied to each of the previously described embodiments of my invention. In this construction, the coin-moving plunger 48 is pivotally connected by a transverse inwardly extending link 204 to the lower end of a long downwardly extending arm 205 of a bell-crank lever having a shorter substantially transverse outwardly extending arm 206 and fulcrumed on a pivot stud 207 on the supporting plate 181 at the left of the coin chute 25 as viewed from the rear in Figure 21. A coiled extension spring 208 has one end connected, by means of a stud 209, to the longer lever arm 205 with its other end anchored to a stud 210 on the plate 181 at the right of the coin chute 25 (Figure 21). Thus this spring 208 will have a tendency to maintain the coin plunger 48 at its retracted or normal outer position, with the transverse arm 206 of the bell-crank lever at an elevated position, as shown in Figures 19 and 21.

The coin plunger 48 is operated in its coin-pushing movement by means of a vertical manually depressible plunger or operating rod 211, the outer upper end of which carries a button or knob 212 forming a finger piece. This operating rod 211 is shown as extending just at the right of the coin chute 25 where it is guided through a pair of similar brackets 213, 213, which are secured to the supporting plate 181. The lower end of this operating rod 211 has a pivotal connection to the outer end of the transverse bell-crank arm 206, whereby manual depression of the finger piece 212 will transmit inward coin-pushing movement to the coin plunger 48, and when the coin plunger is set free to be returned or retracted by the spring 208 this spring at the same time will restore the operating rod 211, together with its finger piece 212, to the upper normal position shown in the drawings. The downward movement of the depressible operating rod 211 has been found to be more convenient 105 of operation than a plunger stem at the side.

Figures 22 to 26 inclusive illustrate a desirable modification in the coin controlled mechanism of the coin controlled timed service device of my invention. In this modification it is only necessary to operate the coin-pushing plunger 48 manually once in all, for moving the first-inserted lowermost coin, such as the coin 28, into operative position, in the same manner as hereinbefore described. After that the service rendered 110 is automatically continuous indefinitely, so long as there is a reserve supply of coins, such as the coins 214, 214, in the coin chute 25 and the timing clock is kept wound. This improved modification may be equally well employed with all of 115 the previously described forms of my invention.

For the sake of clarity of understanding, it should be noted that the lower transverse tail arm or finger portion of the long depending or downwardly extending lever arm 86 is not required in 120 carrying out some of the modifications, but is shown in Figures 22 and 23 for the reason that this finger extension would be required in installing this modification on the first form of the device of my invention as described with reference 125 to 130

to Figures 1 to 15 inclusive, where it has a function to perform. It is immaterial in the case of the modifications shown in Figures 18 to 21 inclusive, since while such finger extension is not 5 there required, it would be entirely innocuous. However, in the modification illustrated in Figures 16 and 17, this lower tail arm or finger extension of the lever arm 86 would need to be left off, and is there omitted, since in that single 10 particular instance the presence of such a finger portion would interfere with the manner of operation of other parts, as there shown and described.

In this construction shown in Figures 22 to 26 inclusive, it is advisable to insert a number of reserve coins 214. When the coin-pushing plunger 48 is manually operated, it moves the first or lowermost coin 28 beneath and lifts the cam end 106, in the same manner as hereinbefore described. As this coin 28 is pushed out of the coin chute 25, the coin 214 next above will be supported on the top of the coin plunger 48, which slides beneath it. When this coin plunger is retracted by its spring, which in this instance may 25 take place at once, this next coin 214 will drop down upon the bottom 27 of the coin chute 25, in replacement of the used coin 28, and with the adjacent edges of these two coins 28 and 214 close together, as will be evident from Figure 22. 30 This form of my invention has a modified coin ejector, together with modifications in other parts co-operative therewith, so that thereby the coin ejector is utilized for successively advancing or pushing the reserve coins 214, 214, into operative 35 position beneath the cam end 106, the lowermost one of these coins being thus advanced automatically at the termination of each timed period of service, e. g., twenty-four hours, this modified coin ejector being operated to move forward and 40 back in the same manner and by the same operating means therefor as has been hereinbefore described with reference to the coin ejector 74.

This combined ejector and coin feeder has a rectangular body portion 215 having in its rear face an abrupt notch 216, in which the lug 91 of the lever arm 86 engages and by which this coin feeding ejector slide is actuated in each of its opposite directions of movement. The slide-way provided for the coin plunger 48 and ejector 50 slide 215 by the bracket 75 has through it a rather large longitudinally extending slotted opening 217 for accommodating both the operating lug 91 for the ejector 215 and a pivot pin 218 on the coin plunger 48 for its operating link 55. The body 215 of the ejector is prolonged inwardly, or towards the left as viewed in Figures 22, 24, 25 and 26, in the general shape of a flat terminal blade 219 which forms a rear end shoulder 220 on the body 215 where it joins the 60 latter and has a flat abrupt squared free end 221. This blade 219 is in general of rectangular outline, its length being substantially equal to the diameter of one of the coins and with its upper edge extending above the top of the body 215 to 65 substantially an even level with the top face of the coin plunger 48. This upwardly projecting edge portion of the blade 219 is beveled at the rear to form a downwardly and rearwardly inclined wedge face 222.

In the normal retracted position of the ejector 70 slide 215 shown in the drawings, its blade 219 extends across the coin chute 25 immediately above its bottom closure 27 and just below the lower end of its rearwardly grooved main plate. 75 One end of a rather weak leaf spring 223 is se-

cured on the front face of the main frame plate 16. The free end portion of this spring is shown as of a rounded S-shape and presses somewhat lightly against the front face of the blade 219, through an opening 224 through the frame plate 80 16. It will be noted from Figures 23, 24 and 25 that the ejector slide 215 has some freedom of movement or play horizontally from front to rear, especially at the inner free end 221 of its blade 219, due to the thinness of the latter. This provides for the pressing rearward, by the spring 223, of this end of the blade 219 to the position thereof shown in Figure 25 when there is no coin in the coin chute 25, and for the deflection of this blade 219 forwardly with its front face closely adjacent to the rear face of the frame plate 16, in opposition to the pressure of the spring 223, as shown in Figure 24, when there is a coin 28 on the bottom 27 of the coin chute 25. The weight of a descending coin impressed against 95 the wedge face 222 will readily accomplish such deflection, as will be evident from Figure 25.

The automatic coin-feeding operation is as follows:

It is to be noted from the drawings that a coin 100 in the position of the coin 28 (Figures 22 and 24) is not only directly in the path of inward coin-feeding movement of the inner end of the coin-pushing plunger 48, but is also in like manner directly in the path of inward movement of the 105 shoulder 220 on the coin ejector body 215, which is disposed immediately beneath the coin plunger 48, as is shown in Figures 22 to 25 inclusive. Therefore, with two coins at the same lower level, one supported on the ledge 79 and holding up the 110 cam end 106, and the other in the coin chute 25 and supported by its bottom 27, it is manifest that if the latter coin be moved and fed forward to a position on the ledge 79 beneath the cam end 106, then the first-used coin will be ejected 115 by the second coin, with the cam end 106 then held up by this latter or second coin. In such a transition, the cam end 106 will ride from the top edge of the first coin onto the top edge of the second or advancing coin, without this cam 120 end 106 being objectionably disturbed. In order to assure a smooth and even action in such a substitution of coins beneath the cam end 106, this particular cam end 106 is shown as somewhat more flattened and level than those in the 125 preceding constructions.

The second coin to be used will be thus automatically fed forward into operative position beneath the cam end 106 by the coin-feeding shoulder 220 on the ejector 215, the ejector blade 219 130 at this time being between the flat side of the coin being moved and the rear face of the frame plate 16, as shown in Figure 24. When the ejector 215 is retracted, at the end of a period of service, it clears the coin chute 25 for the descent 135 of the next succeeding coin 214 into the lowermost position, which in Figures 22 and 24 is shown as occupied by the first-inserted coin 28. This succeeding coin will thus begin to descend as soon as the shoulder 220 has cleared its vertical diameter and will drop to its final position when this shoulder has cleared its horizontal diameter.

The above described operation will be automatically repeated, once for each period of service, without intermission or interruption of the service between such periods, so that thereby the service will be automatically continued so long as there remains a second coin 214 held in reserve in the coin chute 25 to take the place of the one 150

- previously used and fed into operative position by the shoulder 220 of the ejector 215. The very last coin 214 in the coin chute 25 on its bottom 27 will in like manner be fed forward by the 5 shoulder 220 and operatively positioned beneath the cam end 106. Should the ejector 215 be retracted in the absence of another coin on the coin chute bottom 27, then its inner end, carrying the blade 219, will be tilted rearwardly, by the spring 10 223, to the position shown in Figure 25, with the end 221 of this blade now in line with the coin which was last positioned beneath the cam end 106.
- However, it is still not too late to insert a coin, 15 in which case the blade 219 will be moved by the inserted coin from its rearward Figure 25 position to its forward Figure 24 position. In order to prevent automatic discontinuance of service, in the manner already described, for any of the 20 preceding constructions, at the end of the period paid for by this last coin, another coin must be inserted into the coin chute 25 before the latter has been blocked by the next forward movement of the ejector 215. Should no coin be inserted 25 in time, then the end 221 of the ejector blade 219 will eject the last-inserted coin, and at the termination of this period of service the ejector 215 will be again returned to the position thereof shown in Figure 25. It will then be necessary 30 to make use of the coin plunger 48 for initiating a subsequent period of service.
- It is obvious that various changes and alterations may be made in the constructions shown in the accompanying drawings and above particularly described, within the principle and scope of my invention as defined in the appended claims. Also I do not limit myself specifically to shape, size, or materials, nor to specific relationship of parts, these being given simply as a means for 35 clearly describing my invention.
- What I claim is:—
1. In a coin controlled timed service device, in combination, a spring-operated timing clock to be in timing operation throughout a period of service, releasable restraining means normally preventing this clock from running, a coin controlled mechanism, a service mechanism, means operated by the coin controlled mechanism for releasing said restraining means to start the timing clock running and concomitantly acting upon the service mechanism to inaugurate the service, means operated by the timing clock to operate said restraining means to stop the clock automatically and concomitantly acting upon the service mechanism to discontinue the service automatically after a predetermined interval of time has elapsed, said coin controlled mechanism including a movably mounted coin-moving part manually movable away from a normal position for moving an inserted coin, a releasable latch normally locking said coin-moving part at its normal position, manually operable spring-winding means for said timing clock, and means operated by the spring-winding means for releasing said latch thereby to unlock said coin-moving part. 40
  2. In a coin controlled timed service device, in combination, a movably mounted coin-moving part operable for moving and repositioning an inserted coin, a movably mounted coin-operated service-controlling part to be operated by the moving coin and maintained at its operated position by the repositioned coin, a service-supplying element having one movement for inaugurating the service and having another movement for discontinuing the service, a timing clock operat- 45
  - ing throughout a period of service, means operated by the coin-operated movement of said coin-operated service-controlling part for inaugurating the service and for concomitantly initiating the timing operating of the timing clock, means controlled by the timing clock for automatically discontinuing the service after a predetermined interval of time has elapsed, means operated by the timing clock for automatically ejecting said repositioned coin during the continuance of the period of service being rendered, and means controlled by the timing clock for causing the service to be continued after the ejection of the coin until the full predetermined period of time has elapsed. 50
  3. In a coin controlled timed service device, in combination, a movably mounted coin-moving part movable away from a normal position for moving and repositioning an inserted coin, a movably mounted coin-operated service-controlling part to be operated by the moving coin and maintained at its operated position by the repositioned coin, a service-supplying element having one movement for inaugurating the service and having another movement for discontinuing the service, a spring-operated timing clock to be in timing operation throughout a period of service, releasable restraining means normally preventing this clock from running, means operated by the coin-operated movement of said coin-operated service-controlling element for inaugurating the service and for concomitantly releasing said restraining means thereby to start the timing clock running, means controlled by the timing clock for automatically discontinuing the service after a predetermined interval of time has elapsed and for concomitantly operating said restraining means to stop the clock, means operated by the timing clock for automatically ejecting said repositioned coin during the continuance of the period of service being rendered, and means controlled by the timing clock for causing the service to be continued after the ejection of the coin until the full predetermined period of time has elapsed. 55
  4. In a coin controlled timed service device, in combination, a movably mounted coin-moving part manually movable away from a normal position for moving an inserted coin, a releasable latch normally locking said coin-moving part at its normal position, a movably mounted coin-operated service-controlling part to be operated by the moving coin, a service-supplying element having one movement for inaugurating the service and having another movement for discontinuing the service, a spring-operated timing clock to be in timing operation throughout a period of service, releasable restraining means normally preventing this clock from running, means operated by the coin-operated movement of said coin-operated service-controlling element for inaugurating the service and for concomitantly releasing said restraining means thereby to start the timing clock running, means controlled by the timing clock for automatically discontinuing the service after a predetermined interval of time has elapsed and for concomitantly operating said restraining means to stop the clock, manually operable spring-winding means for the timing clock, and means operated by the spring-winding means for releasing said latch thereby to unlock said coin-moving part. 60
  5. In a coin controlled timed service device, in combination, a unidirectionally rotative main operating member, means including a source of en- 65

ergy for impressing unidirectional torque upon said member, a service-supplying element having one movement for inaugurating the service and having another movement for discontinuing the service, the inauguration and discontinuation of the service being altogether dependent upon such movements of the service-supplying element, means connecting said main operating member with said service-supplying element for operating the latter in each of its said movements, timing means in control of the operation of said main operating member thereby to cause the latter to transmit movement to said service-supplying element for automatically discontinuing the service after a predetermined interval of time has elapsed, and normally ineffective coin controlled means in control of said timing means thereby to cause the said main operating member to transmit movement to said service-supplying element for inaugurating the service.

6. In a coin controlled timed service device, in combination, a movably mounted coin-moving part operable for moving and repositioning an inserted coin, a movably mounted coin-operated service-controlling part to be operated by the moving coin and maintained at its operated position by the repositioned coin, a service-supplying element having one movement for inaugurating the service and having another movement for discontinuing the service, a unidirectionally rotative main operating member, means connecting said main operating member with said service-supplying element for operating the latter in each of its said movements, means operated by the coin-operated movement of said coin-operated service-controlling part for inaugurating the service, a timing clock, means controlled by the timing clock for automatically discontinuing the service after a predetermined interval of time has elapsed, means operated by the timing clock for automatically ejecting said repositioned coin during the continuance of the period of service being rendered, means controlled by the timing clock for causing the service to be continued after the ejection of the coin until the full predetermined period of time has elapsed, and power means providing energy for the automatic operation of said timing clock and said main operating member.

7. In a coin controlled timed service device, in combination, a movably mounted coin-moving part operable for moving and repositioning an inserted coin, a movably mounted coin-operated service-controlling part to be operated by the moving coin and maintained at its operated position by the repositioned coin, a service-supplying element having one movement for inaugurating the service and having another movement for discontinuing the service, a unidirectionally rotative main operating member, means connecting said main operating member with said service-supplying element for operating the latter in each of its said movements, a timing clock operating throughout a period of service, means operated by the coin-operated movement of said coin-operated service-controlling part for initiating the timing operation of the timing clock and for concomitantly initiating the operation of said main operating member for thereby transmitting movement to said service-supplying element for inaugurating the service, means controlled by the timing clock for transmitting another movement from said main operating member to said service-supplying element for automatically discontinuing the service after a predetermined interval

of time has elapsed, means operated by the timing clock for automatically ejecting said repositioned coin, and power means providing energy for the automatic operation of said timing clock and said main operating member.

8. In a coin controlled timed service device, in combination, a movably mounted coin-moving part operable for moving and repositioning an inserted coin, a movably mounted coin-operated service-controlling part to be operated by the moving coin and maintained at its operated position by the repositioned coin, a service-supplying element having one movement for inaugurating the service and having another movement for discontinuing the service, a unidirectionally rotative main operating member, means connecting said main operating member with said service-supplying element for operating the latter in each of its said movements, a timing clock operating throughout a period of service, means operated by the coin-operated movement of said coin-operated service-controlling part for initiating the timing operation of the timing clock and for concomitantly initiating the operation of said main operating member for thereby transmitting movement to said service-supplying element for inaugurating the service, means controlled by the timing clock for transmitting another movement from said main operating member to said service-supplying element for automatically discontinuing the service after a predetermined interval of time has elapsed, means operated by the timing clock for automatically ejecting said repositioned coin during the continuance of the period of service being rendered, means controlled by the timing clock for causing the service to be continued after the ejection of the coin until the full predetermined period of time has elapsed, and power means providing energy for the automatic operation of said timing clock and said main operating member.

9. In a coin-controlled timed service device, in combination, a unidirectionally rotative main driving member, means including a source of energy for impressing unidirectional torque upon said member, a service-supplying element mounted for to and fro movement to render the service available upon movement of said element in one direction and to discontinue such service upon return movement of said element, connecting means between said main driving member and said service-supplying element through which rotative movement of said main driving member causes first movement in said one direction to be imparted to said service-supplying element to inaugurate the service and then subsequently causes return movement to be imparted to this element for discontinuing the service, timing means in control of the service-discontinuing operation of said main driving member for automatically discontinuing the service after a predetermined interval of time has elapsed, coin controlled mechanism in control of the timing means and said main driving member for thereby inaugurating the service, and a valve member connected into said service-supplying element to form a feature thereof and mounted to have to and fro opening and closing movement imparted thereto by the respective said movements in the one direction and in the other direction of said service-supplying element.

10. In a coin controlled timed service device, in combination, a coin controlled mechanism comprising a movably mounted coin-moving part to be operated for moving and repositioning an in-

- serted coin, a coin-operated part to be moved away from a normal position by the moving coin and maintained at its operated position by the repositioned coin, and an ejector for discharging the repositioned coin; a timing clock having timing operation throughout a period of service; and a service mechanism comprising a timing wheel operated by said clock to make a single rotation only demarking a predetermined period of service, a cam track on the timing wheel having a depression therein, a timing pin carried by the timing wheel, a service-supplying element movable between a service-supplying position and a normal no-service position, an operating arm for said service-supplying element, a system of pivoted operating arms interconnected with one another for concomitant pivotal movement, said system carrying said coin-operated part and being operatively connected with said service-supplying element operating arm and having a cam follower for said cam track normally seated in its said depression, a spring acting upon said system and urging it towards its normal no-service position, means for initiating the timing operation of said clock when said system is moved away from its normal position by means of a moving coin for inaugurating the service and removing said cam follower out of said cam track depression, and for discontinuing the timing operation of said clock when said system is automatically returned to its normal position by its spring for discontinuing the service and reseating said cam follower in said cam track depression, and a member automatically operated by said timing pin for operating said ejector for discharging said repositioned coin during the continuance of the service with said system of arms then maintained at its coin-operated position for thus maintaining the service and the timing operation of said clock until the end of the predetermined period by means of said cam follower riding upon said cam track until it seats in said depression.
11. In a coin controlled timed service device, in combination, a system of pivoted operating arms interconnected with one another for concomitant pivotal movement between a normal no-service position and an operated service-providing position, a spring acting upon said system and urging it to its normal no-service position, a coin-operated part carried by said system for operating it against the force of its said spring, a service-supplying element connected with said system for supplying service when said system is operated away from its normal position, a cam follower carried by said system, means for moving a coin to operate said system away from its normal position, a rotatable timing cam acting upon said cam follower for prolonging the service and then for terminating the service at the completion of one rotation only of said cam, a timing clock for rotating said cam, and means controlled by the coin-operated movement of said system of arms for initiating the rotative movement of said cam and controlled by the spring-operated cam-controlled movement of said system for automatically stopping the rotative movement of said cam at the end of its said one rotation concomitantly with the automatic discontinuance of the service after a predetermined interval of time has elapsed.
12. In a coin controlled timed service device, in combination, a pivoted rocking operating lever having three divergent operating arms and operable for pivotal movement between a normal no-service position and an operated service-provid-
- ing position, a spring acting upon said lever for returning it from its operated position to its normal position, a coin-operated part carried by one of said arms for operating said lever against the force of its said spring, means for moving a coin to operate said coin-operated part, a service-supplying element connected with another of said arms for supplying service when said lever is operated away from its normal position, a cam follower carried by the remaining arm of said lever, a timing clock, a rotatable timing cam operated by said clock to make a single rotation only demarking a predetermined period of service and acting upon said cam follower for prolonging the service and then for terminating the service at the completion of said one rotation of said cam, and means controlled by the rocking of said lever away from its normal position for initiating the rotation of said cam and controlled by the return movement of said lever for automatically stopping the rotation of said cam at the end of its said one rotation concomitantly with the automatic discontinuance of the service after a predetermined interval of time has elapsed.
13. In a coin controlled timed service device, in combination, a pivoted rocking operating lever having three divergent operating arms and operable for pivotal movement between a normal no-service position and an operated service-providing position, a spring acting upon said lever for returning it from its operated position to its normal position, a coin-operated part carried by one of said arms for operating said lever against the force of its said spring, means for moving a coin to operate said coin-operated part, a service-supplying element connected with another of said arms for supplying service when said lever is operated away from its normal position, a cam follower carried by the remaining arm of said lever, a timing clock to run throughout the continuance of a period of service, a timing wheel operated by said clock to make a single rotation only demarking a predetermined period of service, a cam track carried by the timing wheel on which said cam follower rides for thereby continuing the service in the absence of said coin and having a depression therein in which said cam follower is seated by said spring in the normal no-service position of said lever, and means made effective by said lever for starting the timing clock to run concomitantly with the inauguration of service by means of said coin and for automatically stopping said clock concomitantly with the automatic discontinuance of service by the seating of said cam follower in said cam track recess.
14. In a coin controlled timed service device, in combination, a manually operable plunger for moving an inserted coin, a spring for automatically returning the operated said plunger to its normal position, a latch for automatically locking said plunger at its normal position, a spring-operated mechanism for operating said device, spring-winding means for said mechanism and means operated by said spring-winding means for operating said latch to unlock said plunger.
15. In a coin controlled timed service device, in combination, a manually operable plunger for moving an inserted coin, a spring for automatically returning the operated said plunger to its normal position, a latch for automatically locking said plunger at its normal position, an operating mechanism for said timed service device, a spring for operating said mechanism, spring-winding means for said spring, a timed cam normally having an ineffective relation to said latch,

and a speed-reducing operating connection from said spring-winding means to said cam for operating said latch to unlock said plunger just before the winding of said spring is completed and 5 to restore said cam to its normal position as said spring subsequently begins to unwind from its winding end.

16. In a coin controlled timer service device, in combination, a manually operable plunger for 10 moving and repositioning an inserted coin, a coin-operated part to be moved away from its normal position by the moving coin and maintained at its operated position by the repositioned coin until a subsequent time, a spring for restoring said coin- 15 operated part to its normal position, a timing clock for said timed service device, an ejector operated by the timing clock to discharge the repositioned coin automatically during the continuance and before the termination of a predetermined period 20 of service to be rendered by said device, and means automatically operated by the timing clock for maintaining said coin operated part at its operated position during the remainder of the predetermined period of service and then re- 25 leasing it to be restored by its spring to its normal position.

17. In a coin controlled timed service device, in combination, a downwardly directed coin chute, a manually operable plunger for moving a coin 30 transversely out of the lower end of the coin chute and repositioning it until a subsequent time, a spring for restoring the operated coin-moving plunger to its normal position, a timing clock for said timed service device, an ejector operated by 35 the timing clock to discharge the repositioned coin automatically at said subsequent time and movable transversely across the lower end of the coin chute, a coin guard having a one way lost motion connection with the coin-moving plunger to be 40 moved thereby in delayed relation therewith transversely into the coin chute above the path of the ejector and there maintained for blocking the descent of another coin until after the ejector has been operated in its ejecting movement, a 45 one-way pawl engageable with said coin guard for thus maintaining it in the coin chute, a restoring spring tending to move said coin guard out of the coin chute, and means operated automatically by the timing clock to release said pawl 50 after the ejector has been operated thereby to clear the coin chute for the descent of the next coin.

18. In a coin controlled timed service device, in combination, a downwardly directed coin chute, 55 a manually operable plunger for moving a coin transversely out of the lower end of the coin chute and repositioning it, a spring for restoring the operated coin-moving plunger to its normal position, a coin-operated part to be moved away from 60 its normal position by the moving coin and maintained at its operated position by the repositioned coin, a spring tending to restore said coin-operated part to its normal position, a combined coin feeder and ejector slide movable transversely for- 65 ward and back across the lower end of the coin chute without obstructing the latter to the descent of coins when this coin feeding ejector slide is at its retracted normal position, such ejector slide comprising a body portion forming an inner 70 coin-feeding and ejecting shoulder which normally clears the coin chute, and having a flat blade extension from said shoulder beveled along its upper edge on its side towards said shoulder and terminating in an abrupt free inner ejecting 75 end, a slideway for said ejector slide providing

lateral play for its blade end to the extent of the thickness of an inserted coin, a light spring at the flat side of said blade for shifting the blade to take up such play at its beveled side in the absence of a coin alongside the beveled side of 80 said blade extension and in the path of said shoulder on said body portion, a timing clock for said timed service device, means to be automatically operated by said clock for terminating the service only upon the return of said coin-operated part to its normal position, and means automatically operated by the timing clock during each period of service for operating said ejector slide to move the latter once forward and subsequently back to its normal retracted position, whereby after the repositioning of a first-inserted coin by said coin-moving plunger, then other reserve coins in the coin chute will be periodically automatically repositioned by said ejector slide shoulder and a repositioned final coin will be ejected by 90 said free inner end of the ejector slide thereby to terminate the automatically repeated periods of service.

19. In a coin controlled mechanism, a horizontally disposed coin-feeding ejector slide comprising 100 a straight body portion provided with a coin-feeding and ejecting shoulder and having a flat blade extension from said shoulder beveled along its upper edge on its side towards said shoulder and terminating in an abrupt ejecting end.

20. In a coin controlled mechanism, a horizontally disposed ejector slide comprising a straight body portion provided with a thinner upwardly wedge-shaped blade extension which terminates 110 in an abrupt ejecting end.

21. In a coin controlled timed service device, in combination, a service-supplying element having a rocking operating arm movable to one position for inaugurating the service and to another position for discontinuing the service, an operating link pivotally connected to said arm, a rotatable crank to which said link is connected, a pawl-controlled disc connected to have unitary rotative movement with said crank, a pair of diametrically opposite abutments on said disc 115 which are disposed thereon radially out of circumferential alignment with one another, a power spring for continuously impressing torque upon said disc, a starting pawl arm normally in engagement with one of said disc abutments in 120 a no-service position of said service-supplying element, said pawl being movable into the circular path of said other abutment for inaugurating the service and returnable to its normal position for discontinuing the service, a spring tending 125 to move said starting pawl to its normal position, coin controlled mechanism for moving said starting pawl away from its normal position thereby to inaugurate the service, a timing clock mechanism, and means operated by said 130 clock mechanism for restoring said pawl to its normal position thereby to discontinue the service after a predetermined interval of time has elapsed.

22. In a coin controlled timed service device, 140 in combination, a service-supplying element having a movement to one position for inaugurating the service and having a movement to another position for discontinuing the service, a pawl-controlled disc connected to said service-supplying element to have successive half rotations for successively imparting said movements to said service-supplying element, a pair of diametrically opposite abutments on said disc which are disposed thereon radially out of circumferential 145 150

- alignment with one another, a power spring for continuously impressing torque upon said disc, a starting pawl arm normally in engagement with one of said disc abutments in a no-service position of said service-supplying element, said pawl being movable into the circular path of said other abutment for inaugurating the service and returnable to its normal position for discontinuing the service, a spring tending to move said starting pawl to its normal position, coin controlled mechanism for moving said starting pawl away from its normal position thereby to inaugurate the service, a timing clock mechanism, and means operated by said clock mechanism for restoring said pawl to its normal position thereby to discontinue the service after a predetermined interval of time has elapsed. 23. In a coin controlled timed service device, in combination, a service-supplying element having a rocking operating arm to be moved between a normal no-service position of said element and a service-supplying position thereof, a swinging operating lever extending in the general direction of said operating arm and pivotally connected thereto, a spring biasing said lever towards the service-supplying position of said element, a fulcrum pivot for said lever, a planetary gear carried by said lever, a normally locked idler gear wheel at all times engaged by said planetary gear substantially on a radius from the fulcrum of said lever passing through the axis of said planetary gear, a timing clock mechanism for said timed service device, a train of power-multiplying gearing connecting said clock mechanism to said planetary gear including an initial gear having torque impressed thereon by said clock and a gear coaxial with the fulcrum of said lever and having engagement with said planetary gear with said torque transmitted by said train of gearing and impressed upon said planetary gear in a direction to overcome said biasing spring, a releasable lock for said idler gear wheel normally engaged with the teeth thereof, a spring tending to maintain said lock at its normal engaged position, a movably mounted coin-moving part to be operated for moving and repositioning an inserted coin, a coin-operated part to be moved away from a normal position by the moving coin and maintained at its operated position by the repositioned coin, an operating connection between said coin-operated part and said lock to release the latter by movement of said coin-operated part away from its normal position thereby to render said biasing spring effective to inaugurate the service, an ejector for discharging the repositioned coin, and means automatically operated by the timing clock mechanism for operating said ejector to discharge the repositioned coin in advance of the time for discontinuing the service, whereby said idler gear wheel will be again locked so that thereby said torque impressed upon said planetary gear will become effective to swing said operating lever against the force of its said biasing spring so as thereby to return said service-supplying element to its normal no-service position for discontinuing the service after a predetermined interval of time has elapsed. 25. In a coin controlled timed service device, in combination, a movably mounted coin-moving part operable for moving an inserted coin, a movably mounted coin-operated service-controlling part to be operated by the moving coin, a service-supplying element having one movement for inaugurating the service and having another movement for disconnecting the service, a unidirectionally rotative main operating member, means connecting said main operating member with said service-supplying element for operating the latter in each of its said movements, a timing clock operating throughout a period of service, means operated by the coin-operated movement of said coin-operated service-controlling part for initiating the timing operation of the timing clock and for concomitantly initiating the operation of said main operating member for thereby transmitting movement to said service-supplying element for inaugurating the service, means controlled by the timing clock for transmitting another movement from said main operating member to said service-supplying element for automatically discontinuing the service after a predetermined interval of time has elapsed, and power means providing energy for the automatic operation of said timing clock and said main operating member. 26. In a coin-controlled timed service device, in combination, a movably mounted coin-moving part operable for moving an inserted coin, a movably mounted coin-operated service-controlling part to be operated by the moving coin, a service-supplying element having one movement for inaugurating the service and having another movement for discontinuing the service, said service-supplying element including a valve

member to be moved to open service-inaugurating position by the said one movement of the service-supplying element and to be moved to closed service-discontinuing position by the said another movement of the service-supplying element, a unidirectionally rotative main operating member, means connecting said main operating member with said service-supplying element for operating the latter in each of its said movements, a timing clock operating throughout a period of service, means operated by the coin-operated movement of said coin-operated service controlling part for initiating the timing operation of the timing clock and for concomitantly initiating the operation of said main operating member for thereby transmitting movement to said service-supplying element and its valve member for inaugurating the service, means controlled by the timing clock for transmitting another movement from said main operating member to said service-supplying element and its valve member for automatically discontinuing the service after a predetermined interval of time has elapsed,

and power means providing energy for the automatic operation of said timing clock and said main operating member.

27. In a coin controlled timed service device, in combination, a movably mounted coin-moving part operable for moving and repositioning an inserted coin, a movably mounted coin-operated service-controlling part to be operated by the moving coin and maintained at its operated position by the repositioned coin, a timing clock operating throughout a period of service, means controlled by the timing clock for automatically discontinuing the service after a predetermined interval of time has elapsed, means operated by the timing clock for automatically ejecting said repositioned coin during the continuance of the period of service being rendered, and means controlled by the timing clock for causing the service to be continued after the ejection of the coin until the full predetermined period of time has elapsed.
